UNITED STATES PATENT OFFICE.

FREELAND W. OSTROM, OF BRIDGEPORT, AND JOHN W. BOYNTON, OF STRATFORD, ASSIGNORS TO THE WHEELER & WILSON MANUFACTURING COMPANY, OF BRIDGEPORT, CONNECTICUT.

CUTTING MECHANISM FOR BUTTON-HOLE SEWING-MACHINES.

SPECIFICATION forming part of Letters Patent No. 404,427, dated June 4, 1889.

Application filed May 25, 1889. Serial No. 203,307. (No model.)

To all whom it may concern:

Be it known that we, FREELAND W. OSTROM, of Bridgeport, and JOHN W. BOYNTON, of Stratford, county of Fairfield, and State of Connecticut, have invented an Improvement in Sewing-Machines for Stitching Button-holes, of which the following description, in connection with the accompanying drawings, specification, like letters on the drawings representing like parts.

This invention is intended to be an improvement upon that class of button-hole stitching and cutting mechanism which is described in United States Patents Nos. 303,453 and 303,454 and the modification of the former patent, as represented by United States Patent No. 303,557.

Herein the invention relates more especially to mechanism for cutting the slits in the material while held by the clamp and to means for positively actuating the said cutting mechanism at the proper time. We have also provided the machine with devices whereby the cutting mechanism may be operated but once for each button-hole, and whereby the cutting mechanism may be instantly thrown out of operation whenever desired—as, for instance, should it be desired to turn backward the feeding mechanism of the clamp to correct faults in the stitching. This may be done even after the cloth-clamp has completed its movement to finish the button-hole, or after the hole or slit has been cut, the cutting mechanism so thrown out of operation relatively to the other moving parts of the machine not being again operated while the clamp is being moved to enable said faults to be corrected.

The particular features in which our invention consists will be hereinafter described, and specified in the claims.

Figure 1 is a rear side elevation of a button-hole-stitching machine embodying our invention, parts of the frame-work being broken out to show working parts; Fig. 2, a partial plan or top view of the front end of the overhanging arm with part of the cloth-plate and clamp and feed-wheel and cam-disk. Fig. 3 is a front elevation of the overhanging arm. Fig. 4 is a section of Fig. 3 in the dotted line $x x$; Fig. 5, an elevation and section of the upper sleeve-like bearing for the cutter-bar; Fig. 6, a detail of the collar a^4 ; and Fig. 7 a detail of the arm A^5 and its pin a^8 .

The frame-work of the machine, consisting of the cloth-plate A and overhanging arm A^1 , the needle-bar-actuating rock-shaft A^2 , the needle-bar A^3 , needle A^4 , arm A^5 , link A^6 , the link A^7 , rotating shaft A^8 , and the stitch-forming mechanism co-operating with the said needle, preferably a hook, (not shown,) are all common to the Wheeler & Wilson machine, style No. 10, so need not be herein further described.

The cloth-clamp composed of the members G , G' , G^2 and foot H , as well as the ratchet-toothed wheel D^3 and feed-clamp-actuating disk E , having at its under side the usual groove for actuating devices below it to impart movement to the said clamp, are also old and substantially such as shown by like letters in United States Patent No. 303,453.

The devices between the feed-clamp-actuating disk and the member G of the clamp are herein supposed to be identical with those shown in United States Patent No. 303,557; but as the particular means intermediate the feeding-disk and the clamp to actuate it to move the material under the needle to stitch the button-hole are not herein claimed, it is deemed unnecessary to describe such devices in detail.

The cutter-carrying bar n^5 , extended upward through suitable bearings in the overhanging arm, the cutter n^6 at its lower end, and the spring o , to lift the cutter-carrying bar after the same shall have been depressed, are substantially the same as in United States Patent No. 303,454, where like parts are designated by like letters. The bushing a , constituting the lower bearing for the bar n^5 , is chambered (see Fig. 1) to receive the lower end of the spring o , and the under side of the collar a^4 , attached to the said bar by the screw a^2 , is also chambered to receive the upper end of the said spring, such construction of the said bearing and collar enabling the ends of the spring to be held externally, thereby obviating tendency of the spring to bend laterally under operative strains.

The bar n^5 has fast on it a second collar a^4 , having a finger a^5 , (shown separately in Fig. 6,) which depends below the top of the collar a^4 for a sufficient distance to prevent the stud a^8 , carried by the usual arm A^5 of the needle-bar-actuating rock-shaft, from passing below the lower end of the said finger in case the cutter-bar is tripped, as will be described, before the stud a^8 completes its upward movement. The spring o is herein shown as so connected to the bushing a and to the cutter-bar at or near the collar a^4 as to cause the said spring to normally turn the cutter-bar in such direction as to place the cutter n^6 at its lower end central with the line of stitching.

The cutter-bar is extended through a tubular bearing a^6 , cut away at one side (see Fig. 5) to form a straight guiding-surface a^7 , against which the pin a^9 in the bar n^5 is borne by the spring o whenever the beak b of the tripping mechanism is removed from contact with the stud b' , attached to the upper end of the bar n^5 above the bearing a^6 , and the stud a^8 rises above the collar a^4 .

The bar n^5 above the collar a^4 is surrounded by a short spring b^2 , which, rising and falling with the bar n^5 , acts as a buffer between the said collar a^4 and the lower end of the upper bearing for the said bar. The beak b has its face which comes in contact with the stud b' made cam-shaped, so that as the spring o lifts the cutter-bar into its normal position the stud b' , preferably having a roller-surface, by acting against the said beak, will cause the partial rotation of the said bar n^5 in opposition to the tension of the spring o , the cutter n^6 being thereby turned aside out of the line of travel of the needle-bar. The cutter-bar, having reached its normal height, is held with the cutter turned aside, as stated, so long as the beak b remains in its normal position against the stop b^3 , it being held in such position by the tension of the spring b^4 , one end of which is attached to the said beak b , while its outer end is seated in an opening of and connected to a part of the overhanging arm, the said spring also serving the purpose of keeping the beak b and the tripping-rod b^5 , to which it is attached by the screw b^6 , in its most elevated position.

So long as the beak b acts against the stud b' to hold the cutter-bar, as shown in Figs. 1 and 3, the finger of the collar a^4 is kept forward out of the line of travel of the stud or pin a^8 , before referred to; but as soon as the beak is turned aside away from the stud b' by a partial rotation of the tripping-rod, as will be described, the spring o , acting on the bar n^5 , brings the upper end of the collar a^4 in the range of travel of the stud a^8 while the latter is descending, and the said stud, acting upon the upper end of the said collar and finger, causes the cutter-bar to be driven down quickly, the line of movement of the cutter n^6 being determined by the pin a^9 on the bar n^5 then operating against the guiding-

wall a^7 of the bearing a^6 . The collar a' at its rear side has a lug b^7 , which, in the descent of the cutter-bar n^5 , comes in contact with a tripping-arm b^8 above a collar c , attached thereto by a suitable set-screw. Above the arm b^8 the tripping-rod b^5 has applied to it loosely a cam-collar c' , having a suitable handle by which it may be turned on the said tripping-rod when it is desired to depress the said tripping-rod and place the arm c^2 thereof below the line of travel of the pin c^3 of the tripping-arm c^4 , attached to or moving in unison with the usual ratchet-toothed feeding-wheel D^3 or the cam-disk E . When the tripping-rod is so depressed, the cam on the cam-collar c' acts against a part of the under side of the overhanging arm, and at such time and while the arm c^2 is held below the line of travel of the tripping-arm c^4 the wheel D^4 and cam-disk E may be revolved in either direction without bringing the pin of the tripping-arm c^4 in contact with the arm c^2 and putting in operation the cutter-bar.

In the operation of stitching the button-hole the toothed wheel D^3 and the disk E will be rotated step by step, in usual manner, as common in the patents referred to, and the button-hole cutter will be held in elevated position with the blade turned aside, the beak b of the tripping-rod resting against the stud b' at the upper end of the cutter-bar, and the arm c^2 at the lower end of the tripping-rod will stand in the line of travel of the pin c^3 , extended from the tripping-arm c^4 . With the parts in this condition, substantially as the stitching for the button-hole is completed, the pin c^3 of the tripping-arm c^4 , in the rotation of the wheel D^3 , will meet the arm c^2 of the tripping device and turn the beak b aside, permitting the spring o of the cutter-bar to turn the latter as soon as the stud a^8 arrives in its highest position, such movement of the cutter-bar placing the cutter in a line centrally with relation to and parallel with and between the two lines of stitching constituting the two sides of the button-hole. This done, the stud a^8 in its descent strikes the upper side of the collar attached to the cutter-bar and causes the cutter-bar to be thrown down quickly, the cutter at its lower end cutting the material held in the clamp and under its foot H , making a slit between the two lines of stitching constituting the button-hole.

Herein it will be seen that the needle-bar derives its motion from the arm A^5 , which carries the stud a^8 , that effects the descent of the cutter-bar; but owing to the fact that the stud a^8 is nearer the center of the needle-bar actuating shaft A^2 than the pin d , (see Fig. 3,) employed to attach the said arm to the link A^6 , it follows that the cutter-bar descends at a slower speed than does the needle-bar, but they both reach their extreme position of descent at the same time and they both reach their highest position at the same time. The

end of the arm b^8 , acted upon by the lug b^7 of the collar a^4 , depresses the tripping-rod b^5 , so that its arm c^2 is placed below the line of travel of the pin c^3 and allows the beak b to 5 resume its normal position under the action of the spring b^4 , so that the cutter-bar, in its first ascent after cutting the slit, is positively turned aside and thrown out of operative position.

10 Referring to Fig. 4, the collar a^4 on the cutter-bar is in such position as to remove the lug a^5 from the path of movement of the stud a^8 , and the lug b^7 is out of line with the arm b^8 , connected to the tripping-rod; but it will 15 be obvious that the rotation of the cutter-bar sufficiently to place the lug a^5 under the descending stud a^8 also places the lug b^7 of the collar a^4 , also fixed to the cutter-bar, immediately over the inner end of the arm b^8 , thus 20 depressing the latter. As the tripping-rod rises, as stated, the arm c^2 rises with it, and at the rear side of the pin c^3 , so that in the further movement of rotation of the wheel D^3 in its working direction the arm c^2 cannot be 25 again struck so as to cause the cutter to cut twice in the same place or in the same button-hole. In the descent of the cutter-bar the lug b^7 does not strike the arm b^8 until the cutter-bar has almost completed its downward 30 thrust.

In case of any imperfection—such as skipping stitches or breaking threads—imperfections which need to be rectified—or when the wheel D^3 and disk E are to be turned back 35 for any reason, the cam-collar c' will be turned back to depress the tripping-rod and remove its arm c^2 out of the range of movement of the pin c^3 when the wheel D^3 is again being moved forward and the disk E is acting to move the 40 clamp while the stitching is being done over again, the arm c^2 being retained down below the pin c^3 until after the tripping-arm c^4 again passes the arm c^2 , thus avoiding the necessity of forcing the cutter down through the material a second time.

It will be noticed that the finger a^5 of the collar a^4 is extended downward for a distance equal to the travel of the pin a^8 between the commencement of the movement of the clamp- 50 actuating feed or cam disk and the completion of the upward movement of the said pin a^8 , thus avoiding the possibility of the said pin getting under the end of the said finger, which would cause a lock in the movement of 55 the different actuating parts; but by making the finger a^5 of proper length, as just described, the outer end of the pin a^8 acts to hold the cutter-bar and its attached cutter out of engagement until the said pin reaches the extreme of its upward movement, although the 60 said cutter-bar and its attached cutter and the cam-faced beak b have been forced out of engagement by the contact of the pin c^3 with the arm c^2 through the tripping-rod b^5 . The 65 stud a^8 is secured to the arm A^5 by a nut a^{12} .

We have herein shown, but do not broadly

claim, the combination, with a stitch-forming mechanism, a work-clamp, and mechanism for operating the latter, of a cutter and cutter carrier or bar, a depressor operated by the 70 needle-bar-actuating mechanism, a cam or device rotating in unison with the clamp-operating cam or disk, and connections between the said rotating cam or device and depressor whereby the cutter is thrown into action. 75

We claim—

1. In a button-hole sewing-machine, the combination, with the work-clamp and its operating cam or disk, of a cutter-bar, operating mechanism therefor, a cutter carried by 80 said bar, and a tripping device to throw the cutter-bar-operating mechanism into action, said tripping device having two members, one of which members, as arm or projection c^4 , is connected to and moved in unison with the 85 said clamp-operating cam or disk, and is thus a traveling member, the other member of the tripping device, as the arm or projection c^2 , being normally stationary in the path of movement of a part of the said traveling member, 90 one of the said members being adjustable or movable with relation to the normal path of movement of the said traveling member to enable the latter to pass the said stationary member without engagement therewith when 95 desired.

2. In a button-hole-stitching machine, a feeding-clamp, a cutter-bar, its cutter, the attached collar a^4 , having a finger, a pin or projection, as b' , carried by the cutter-bar, a 100 spring to partially rotate the cutter-bar in one direction, needle-actuating mechanism, and a pin or projection deriving its movement therefrom to strike the said collar a^4 and depress the cutter-bar, combined with a movable beak or arm to co-operate with the said pin or projection of the cutter-bar and retain the cutter with its edge turned aside out of operative position with relation to the material to be cut and tripping mechanism, to operate substantially as described. 105

3. In a button-hole-stitching machine, a feeding-clamp, the cutter-bar and cutter, means to reciprocate and partially rotate the said bar, the tripping-rod having an arm c^2 , 115 the feed-clamp-actuating disk having a projection to act upon the said arm, and a beak to act against a pin or projection of the cutter-bar, combined with a spring to hold the said tripping-rod in its normal position, to operate substantially as described. 120

4. In a button-hole-stitching machine, a cutter, a cutter-bar having a projection b' and a projection b^7 moved in unison with it, means to reciprocate the cutter-bar, a spring to partially rotate the cutter-bar in one direction, a feed-clamp, and a feed-clamp-actuating disk having an attached tripping arm or projection, and a tripping-rod having two arms or projections, one of which holds the cutter-bar turned aside, while the other arm rests in the line of travel of the tripping-arm made 125 130

movable with the said disk, combined with an arm b^8 , projecting from the tripping mechanism and located in the line of travel of the said projection b^7 of the cutter-bar, where-
5 by the latter in its descent moves the tripping-arm longitudinally, substantially as de-
scribed.

In testimony whereof we have signed our

names to this specification in the presence of two subserbing witnesses.

FREELAND W. OSTROM.
JOHN W. BOYNTON.

Witnesses:

ISAAC HOLDEN,
CHAS. C. WILSON.

It is hereby certified that in Letters Patent No. 404,427, granted June 4, 1889, upon the application of Freeland W. Ostrom, of Bridgeport, and John W. Boynton, of Stratford, Connecticut, for an improvement in "Cutting Mechanism for Button-Hole Sewing Machines," an error appears in the printed specification requiring correction, as follows: In the heading the words and figures "application filed May 25, 1889," should read *application filed May 25, 1886*; and that the Letters Patent should be read with this correction therein that the same may conform to the record of the case in the Patent Office.

Signed, countersigned, and sealed this 11th day of June, A. D. 1889.

[SEAL.]

CYRUS BUSSEY,
Assistant Secretary of the Interior.

Countersigned:

C. E. MITCHELL,
Commissioner of Patents.
